Primary Examiner—Celia Murphy**Attorney, Agent, or Firm**—Jacobson, Price, Holman & Stern, PLLC**[57] CLAIM**

The ornamental design for a combined tread surface and periphery for a shoe sole, as shown and described.

DESCRIPTION

FIG. 1 is a perspective view of a combined tread surface and periphery for a shoe sole showing my new design; FIG. 2 is a bottom plan view thereof; FIG. 3 is a right side elevational view thereof; FIG. 4 is a left side elevational view thereof; FIG. 5 is a rear edge elevational view thereof; and, FIG. 6 is a front edge elevational view thereof.

The broken lines showing a shoe upper, and the unshaded portion of the upper surface are for illustrative purposes only and form no part of the claimed design.
